UNITED STATES PATENT OFFICE.

HENRY HOFFA, OF WASHIINGTOM, DISTRICT OF COLUMBIA.

DESIGN FOR A WATCH-CASE.

SPECIFICATION forming part of Design No. 21,748, dated August 2, 1892.

Application filed June 8, 1892. Serial No. 435,999. Term of patent 3½ years.

To all whom it may concern:

Be it known that I, HENRY HOFFA, a citizen of the United States, residing at Washington, in the District of Columbia, have invented a new and original Design for Watch-Cases, 5 of which the following is a specification.

This invention relates to a certain new and original design for watch-cases; and it consists in the ornamentation upon the obverse 10 and reverse side and edge thereof, as will be more fully hereinafter described and claimed.

In the drawings, Figure 1 is a view of the obverse or front portion of the case. Fig. 2 is a view of the reverse or back portion of the 15 case. Fig. 3 is an edge elevation of the case.

Referring to the drawings, the numerals 1 and 2 designate, respectively, the front and back lids of the watch-case, and 3 the rim of

the watch-case. On the front lid 1 is a representation of the Capitol building and above 20 the same is a scroll, as at 4 and 5. On the back lid 2 is a representation of a Grand-Army badge 6. The rim or edge 3 is ornamented, as at 7, and the whole design, as set forth, forms a pleasing and unique souvenir. 25

Having thus described the invention, what is claimed as new is—

The design for a watch-case, substantially as herein described and shown.

In testimony that I claim the foregoing as 30 my own I have hereto affixed my signature in the presence of two witnesses.

HENRY HOFFA.

Witnesses:

HORACE G. PIERSON,
BERNICE A. WOOD.
